A. NAMUR.

REGISTER FRONT.

No. 15,343.

Patented Aug. 26, 1884.

UNITED STATES PATENT OFFICE.

DESIGN FOR A REGISTER-FRONT.

SPECIFICATION forming part of Design No. 15,343, dated August 26, 1884.

Application filed April 5, 1884. Term of patent 14 years.

To all whom it may concern:

Be it known that I, AUGUSTE NAMUR, a citizen of Luxemburg, residing at New York city, in the county and State of New York, have invented and produced a new and original Design for Hot-Air-Register Fronts, of which the following is a specification, reference being had to the accompanying drawings, forming part thereof.

10 My design for hot-air-register fronts is represented in front elevation in three views, Nos. 1, 2, and 3, by the accompanying photographic illustrations; and it consists of the network composed of the four concave-sided center figure of bars *a*, set within the square figure of bars *b*, and having its points or angles connected to the middle of the bars of figure *b*, which is set diagonally within another square figure of bars *c*, and connected at its angles with the middle of the bars of the figure *c*, and the bars of figure *b* are connected at the middle by radial bars *e*, coincident with the points of figure *a*, which bars extend to the angles of figure *c*, and between the center figure, *a*, and the outer figure, *c*, 25 there is a sinuous chain figure, *f*, of substantially square form, but curved at the corners and indented or concaved in the sides, which incloses figure *a*, and partly incloses figure *b*, which it crosses within the angles of said figure. It also crosses the radial bars *e*, and between said radial bars *e* and the angles of figure *b* said chain figure *f* is connected by short bars *g* with the bars of figure *c*. The 30 sides of figure *a* are also connected to the sides of the chain figure *f* at the center of each by bars *h*, and the chain figure *f* may, if desired, be connected with the angles of square figure *b* by bars *i*. For the connection of the center figure, *a*, and the chain figure *f*, I propose to employ bars *h*, and in some cases I propose to arrange a small circular or approximately circular figure consisting of a ring, *j*, in the center of figure *a*, connecting it to the sides of *a* by suitable bars, *k*. These 40 figures *a*, *b*, *c*, and *f*, with the devices *h*, *i*, *j*, and *k*, I arrange in a rectangular frame of square figures, *l*, joined together at diagonal

angles, and also joined at the converse angles to bars *m* and to bars *n*, respectively, on two 50 sides of the register, and on the other two sides said figures *l* join the border-frame *n*. Between the bars *m* and the border-frame *n* I arrange parallel cross-bars *o*. The border-frame is figured on its surface with the parallel bars *p* along each margin, which cross each other at the corners of the frame and inclose a four-pointed figure, *q*, also with cross-bars *s*, near the middle of the long sides of the frame, also inclosing a figure, *q*, and 60 also with the two reverse series of angle-ribs *t*, separated by a diamond figure, *u*, in the spaces between the point figures *q*. In extra long fronts I propose to duplicate the center figures, *a*, *b*, *c*, and *f*, by placing two 65 sets of said figures side by side within one frame *l*, as in Fig. 2, or the figures *a* may be duplicated in two partly-duplicated figures *b*, merging in each other within an elongated frame, *c*, together with an elongated chain figure, as in Fig. 3.

I claim—

1. In a design for a register-front herein shown, the center portion consisting of the center concave-sided figure of bars *a*, within the figure of bars *b*, and having its points or angles connected to the middle of the bars *b*, set diagonally within the square figure *c*, and connected at its angles with the middle of the bars of figure *c*, also connected at the middle by bars *e* radial to the center of figure *a*, with the angles of figure *c*, together with the sinuous chain figure *f*, crossing bars *b* and *e* and connected to them, and also connected to the bars of figure *a* by the bars *h*, 85 as set forth.

2. In a design for a register-front herein shown, the border portion consisting of the inner rectangular border-frame of square figures, *l*, joined together at diagonal angles, 90 and also joined at the converse angles to bars *c*, and to surrounding bars *m* and *n*, as set forth.

3. The design for a register-front herein shown, consisting of the center portion, the inner rectangular border-frame, and the outer

border-frame of upper and lower bars, *m* and *n*, said frame being figured on its surface with the parallel bars *p* along each margin, which cross each other at the corners of the frame 5 and inclose a four-pointed figure, *q*, also with cross-bars *s*, near the middle of the long sides of the frame inclosing other figures *q*, and also with the two reverse series of angle-ribs *t*,

separated by a diamond figure, *u*, in the space between the front figure, *q*, as set forth.

AUGUSTE NAMUR.
